UNITED STATES PATENT OFFICE.

MICHAEL BELLEGAY, OF CHICAGO, ILLINOIS.

DESIGN FOR A COMBINED TELLURION AND CLOCK CASE.

Application filed January 27, 1922. Serial No. 405. Term of patent 3½ years.

To all whom it may concern:

Be it known that I, MICHAEL BELLEGAY, a subject of the King of Great Britain, residing at Chicago, in the county of Cook and State of Illinois, U. S. A., have invented a new, original, and ornamental Design for Combined Tellurion and Clock Case, of which the following is a specification, reference being had to the accompanying drawing, forming a part thereof.

In the drawing: The figure is a perspective of a combined tellurion and clock case embodying my new design.

I claim:

The ornamental design for a combined tellurion and clock case, as shown.

M. BELLEGAY.
